UNITED STATES PATENT OFFICE

168,236

COMPOSITE LENS FOR RUNWAY LIGHTS

Willis A. Pennow, Cleveland, Ohio, assignor to
Westinghouse Electric Corporation, a corpora-
tion of Pennsylvania

Application December 27, 1950, Serial No. 13,602

Term of patent 14 years

(Cl. D48—16)

To all whom it may concern:

Be it known that I, Willis A. Pennow, a citizen of the United States, residing at Cleveland, in the county of Cuyahoga and State of Ohio, have invented a new, original, and ornamental Design for a Composite Lens for Runway Lights, of which the following is a specification, reference being had to the accompanying drawing, forming a part thereof, in which:

Fig. 1 is a side elevational view, taken in the direction of the arrows 1—1 of Fig. 2, of a composite lens for runway lights showing my new design;

Fig. 2 is a top plan view thereof;

Fig. 3 is a side elevational view of the lens shown in Figs. 1 and 2 taken in the direction of the arrows 3—3 of Fig. 2;

Fig. 4 is a bottom plan view of the lens shown in Figs. 1 to 3;

Fig. 5 is a cross-sectional view of the lens shown in Figs. 1 to 4 taken on the line 5—5 of Fig. 2; and

Fig. 6 is a side elevational view of the lens

shown in Figs. 1 to 5 taken from the right of Fig. 2.

I claim:

The ornamental design for a composite lens for runway lights, as shown and described.

WILLIS A. PENNOW.
